UNITED STATES PATENT OFFICE.

RICHARD KIESERLING, SR., OF CINCINNATI, OHIO.

HAT-FASTENER.

SPECIFICATION forming part of Letters Patent No. 682,715, dated September 17, 1901.

Application filed January 7, 1901. Serial No. 42,407. (No model.)

To all whom it may concern:

Be it known that I, RICHARD KIESERLING, Sr., a citizen of the United States, residing at Cincinnati, in the county of Hamilton and 5 State of Ohio, have invented a certain new and useful Improvement in Hat-Fasteners, of which the following is a specification.

The primary object of my invention is to dispense with the hat-pin which is now in such 10 general use for fastening ladies' hats and which is so objectionable on account of the injury it does to the hat and the wearer's scalp and the difficulty which is experienced in properly manipulating the same. I dis- 15 pense with the hat-pin entirely and provide an improved fastener adapted to be secured to the hat or other head-gear and avoid the sharp point necessary in a hat-pin, because the latter must pierce the material of the hat 20 when being fastened. I provide a comb-shaped fastening adapted to be secured to the brim of the hat at its inner edge and to be slid under the hair near and along the scalp where the wearer's hair is thickest, preferably 25 in the arc of a circle, so as to securely fasten the hat to the wearer's head without danger of injury either to the hat or the wearer's scalp or disarrangement of the hair and to be practically out of view when the hat is worn. 30 My invention consists in the parts and in the construction, arrangement, and combinations of parts hereinafter more fully described and claimed.

In the drawings, Figure 1 is a bottom view 35 of a pair of my improved devices shown attached to a hat, one of the combs being shown in inserted and the other in drawn position. Fig. 2 is a perspective view of the guide, and Fig. 3 is a similar view of the comb 40 of my improved device.

A indicates the hat, and B its brim; a, the front, and a' the rear, of the hat.

C is a guide consisting, preferably, of a lower plate 1 and an upper or attaching plate 45 2, secured together in any suitable manner, between which a comb 3 is adapted to slide, preferably in the arc of a circle, upon a pivot 4. The comb 3 has teeth 5, preferably ar- 50 ranged in arcs of circles about the pivot 4, so that the entering-point of each tooth of the comb into the hair may be the point through which the tooth may pass throughout its

length, so as not to disarrange the hair or push it sidewise while the comb is entering and so that the teeth of the comb may be 55 withdrawn along the same lines along which they enter the hair. The guide C is fastened to the brim of the hat, preferably by stitches 6, taking through holes 11, the stitches ex- 60 tending longitudinally of the guide C, so that the guide may swing upon the stitches as on a pivot, thereby enabling the wearer when pushing the comb into the hair in fastening the hat to swing the comb to the de- 65 sired angle from the plane in which it is normally fastened in order to cause the comb to follow the scalp-line in the manner that an ordinary comb would be angled in pushing it into the hair. To aid in inserting and withdrawing the comb, I provide the 70 outer swinging end of the comb with an ex- 75 tension 7, the outer edge of which may have a ridge 8 to aid in grasping the same. The guide C is preferably curved to follow a larger circle than the circle of the inner open- 80 ing of the hat to afford the proper resistance in the manner of a leverage to the displacement of the comb from its normal plane, so that the hat when fastened may be securely held to the head.

I prefer to construct my improved device of celluloid of the "shell" effect of ladies' ordinary combs; but it is obvious that the same may be made of any suitable material or color, but, constructed as I prefer, it is less liable 85 to attract notice when worn, being usually of substantially the color of the hat or the wearer's hair and when noticed being readily mistaken for an ordinary comb. The guide by which it is secured to the hat is narrow 90 and is ordinarily covered when worn by the loose hair beyond the point where the inner edge of the hat-brim sits upon the wearer's head.

In order to limit the withdrawing or the 95 pushing in of the comb, I prefer to provide a tooth with a slot 9, through which a pin 10, secured to the guide, may take. The ends of the slot, striking the pin, limit the inward or the outward movement of the comb. When 100 the comb is withdrawn to its limit, the ends of the teeth are flush with or drawn beyond the edge of the guide, so that the hat may be placed upon the head or removed therefrom

without danger of mussing the hair. When the hat is upon the head and the comb is withdrawn from the hair, the teeth of the comb are drawn through the guide, so that no hair may be withdrawn with the teeth, the guide arresting the hair which might have a tendency to follow the teeth, thereby preventing tangling of the hair with the fastening.

10 It is of course understood that the fasteners are to be made in pairs, one for each side of the hat, preferably in rights and lefts. I prefer to secure the fasteners to the sides of the hat with their middle slightly to the rear 15 of the middle of the side of the head, so that when the comb is pushed into the hair it will take hold of that part of the hair where on a woman's head it is ordinarily thickest, giving to the hat greatest security upon the head.

20 The curves along which the teeth of the comb are forced into the hair cause the teeth to cross the lines along which the hair has been combed in numerous places, thereby affording additional security.

25 The teeth of the comb gradually increase in length with the distance they are located from the pivotal point of the comb. The free ends of the teeth may also collectively describe a curve. When the comb is inserted 30 into the hair and swung from its normal plane to follow the scalp, the curved inner line of the free ends of the teeth permits the ends of all the teeth to follow the scalp-line closely, the free ends of the teeth presenting a line

35 conforming to the shape of the head and at the same time permitting the longer teeth to take under the thickest part of the hair without disarrangement of the latter, holding the hat firmly in place.

40 I claim—

1. In a hat-fastener, the combination with a guide comprising an elongated narrow loop

adapted for attachment to the brim of a hat, of a comb pivoted within the guide and having its free portion adapted for movement therethrough and for projection therefrom, which is provided with a plurality of curved teeth which are substantially coincident with an equal number of arcs of circles struck at varying distances from the pivotal point of the comb as a center, the tips of said teeth collectively describing a curve, and one of said teeth having a curved slot, and a stoppin on the guide which passes through said slot.

2. In a hat-fastener, the combination with a guide composed of connected substantially parallel members disposed in separated arrangement from each other and extensions at the ends thereof having apertures whereby the guide can be connected to the brim of a hat, of a comb pivoted within the guide and having its free portion adapted for movement therethrough and for projection therefrom, which is provided with an extension adapted 60 for use as a fingerhold, said comb having a plurality of curved teeth which are substantially coincident with an equal number of arcs of circles struck at varying distances from the pivotal point of the comb as a center, with the tips of said teeth collectively describing a curve, the nearest tooth to the pivot being provided with a curved slot, and a pin on the guide which lies in said slot and is adapted to limit the movement of the comb 70 in both directions.

In testimony whereof I have signed my name hereto in the presence of two subscribing witnesses.

RICHARD KIESERLING, SR.
